UNITED STATES PATENT OFFICE

OSCAR NYGAARD, OF SAUGUS, MASSACHUSETTS

FURNACE WALL

Application filed February 3, 1930. Serial No. 425,448.

This invention relates to furnace walls and more especially to that type of wall in which a structural steel frame is used in supporting the refractory elements of the wall.

5 In very recent years walls of this type have gone into use to a very substantial extent, and they have well recognized advantages over the purely masonry type of wall in the larger installations, especially those 10 of the air cooled type.

The present invention aims to improve the construction of walls of this character with a view to reducing the weight of the steel required and providing a more economical 15 structure, while still obtaining all the advantages of prior walls of this type.

The nature of the invention will be readily understood from the following description when read in connection with the accompanying 20 drawings, and the novel features will be particularly pointed out in the appended claims.

In the drawings,

Figure 1 is a perspective view, partly in 25 cross-section, illustrating a wall embodying features of this invention;

Fig. 2 is a front elevation of a portion of a wall like that shown in Fig. 1;

Fig. 3 is a vertical sectional view approximately on the line 3—3, Fig. 2; and

Figs. 4, 5 and 6 are sectional views approximately on the lines 4—4, 5—5 and 6—6, respectively, Fig. 2.

Referring more especially to Figs. 1 and 33 3, the construction there shown comprises an inner or front wall section A and an outer or rear wall section B, the face of the front section A being exposed to the fire and forming a wall of the combustion chamber.

40 These sections are separated from each other by an air space C.

In the rear section B is a structural steel frame which includes upright posts 2, shown as consisting of I-beams, and horizontal 45 beams 3, preferably of channel section and riveted to the upright members 2. This rear section also includes a brick wall 4 which is supported on the horizontal beams 3, and a rear sheet metal shell 5 immediately behind 50 the brick wall 4, the shell being bolted to the

frame. Usually a layer 6, Fig. 1, of asbestos millboard, or other insulating material, is interposed between the shell 5 and the rear brick wall 4.

The rear section of the wall is designed to 55 be permanent and should not require repairs for a long period of time. The lining or front wall section, however, is subjected to the disintegrating action of the flame and high temperature gases in the furnace and 60 therefore deteriorates far more rapidly than the rear wall section. Due to these facts it is expected that the front or lining section of the wall will require renewal or repairs from time to time, and the wall is constructed 65 to facilitate these operations.

In order to support the refractory blocks or bricks which make up the greater part of the front section of the wall, a series of supports or hangers 8 are mounted on the structural steel frame in the rear section of the wall. It will be seen from an inspection of Figs. 1 and 3 that each of these hangers includes a hook-shaped upper end a to engage the flange of one of the channel beams 3, and 70 also includes an inclined portion b extending downwardly and forwardly from the part a as well as a substantially upright main section c and an inclined lower end section d extending from the lower end of the main 75 section c and resting against the rear wall section. The main sections c of the hanger lie chiefly or entirely in the front section a of the wall, while the upper and lower end sections b and d extend across the air space C 80 between the front and rear sections A and B. These hangers are of such shape and dimensions as to give them great strength and 85 rigidity.

Considering any two adjacent hangers 90 mounted in horizontal alignment with each other as forming a pair, it will be observed that the lower end portions of the members of each pair are connected by a bar 9 preferably provided with stiffening ribs 10 and 11 95 projecting from the upper and lower faces, respectively, thereof. The opposite ends of this bar rest on flanges or steps e forming integral parts of the hangers 8, and each bar is provided at one end with a hole to receive a 100

- bolt 12, Fig. 6, and at its opposite end with a slot 13 to receive another bolt, both bolts extending through the steps or flanges *e* of their respective hangers and being secured 5 by a cotter pin, or the like, against removal. Above the bar 9 and connecting the members of each adjacent pair of hangers are three bars 15, 16 and 17, the opposite ends of each of the latter bars resting loosely in sockets 10 formed in the hangers, as clearly shown in the drawings. It will be observed that this arrangement permits the expansion and contraction of the horizontal bars 9, 15, 16 and 17 relatively to the hangers, and the mounting 15 of the hangers on the frame in the rear wall section permits the expansion and contraction of these members relatively to the frame as well as to the brick section of the rear wall.
- 20 These horizontal bars hold the refractory bricks or blocks of the front wall section or lining in their properly aligned positions in the wall. These blocks or bricks are made of some highly refractory material such as 25 fire clay, silicon carbide or other compositions, and each brick has a groove extending across the upper surface thereof near its rear edge and a similar groove parallel to it in its lower surface. This is clearly shown 30 in Fig. 3. In laying up this wall the facing preferably is arranged in panels, each panel being held in position by one set of horizontal bars. In Fig. 1 one such panel is shown 35 at the left of the vertical packing joint or expansion joint 18 and above the horizontal joint 19. The lowermost course of blocks 20 in any individual panel is laid first, these blocks resting on the plate or bar 9, and the upright rib 10 of this bar entering the 40 grooves in the lower edges of the blocks or bricks. The bar 15 next is placed in position with the downwardly extending flange of this bar entered in the grooves in the upper edges of the blocks 20. This bar cooperates 45 with the bar 9 in holding the bricks in their properly aligned positions in the facing in the wall, while the bar 9 takes the weight of the bricks. The next adjacent course 21 of 50 bricks is then laid on the bricks 20 and the bar 16 is placed in position, this bar co-operating with the bar 15 in the same manner that the latter cooperates with the bar 9. These operations then are repeated in laying 55 the third and fourth courses 22 and 23, respectively, with the exception that no bar is provided to engage the upper edges of the bricks in the uppermost course 23. Any brick in this course, therefore, can be disengaged from its respective bar 17 by moving 60 the brick upwardly in a direction parallel to the plane of the wall far enough to clear the flange of the bar and then sliding it forward out of the wall. Any of the other bricks 65 can be removed in the same manner as soon

as the bar which engages their upper edges has been removed and the bricks on top of it have been taken away.

In order to lock the bricks in the upper course of each panel in their proper positions in the wall, a course of key bricks 24 is placed on top of the uppermost course 23 in each panel, the key bricks being of such a width that they leave a narrow space between the upper edge of the panel in which they are located and the panel next above it, as indicated at 19 in Figs. 1 and 3. At the upper edge of the wall it may be desirable to pivot a hook such as that shown at 25, Fig. 3, to each of the hangers and to use them to hold a bar in the aligned grooves in the upper edges of the blocks 23.

It will be observed that in this construction each panel is a unit in itself, independent of adjacent panels, and that it is supported solely by its set of bars and by the pair of hangers on which these bars are mounted. Most of the bricks used in the unit are of the same dimensions, extra wide or special bricks being provided, however, to cause the bricks in adjacent courses to break joints as shown in Fig. 1. Those bricks immediately beside the hangers are cut out to accommodate them as shown in Figs. 4 and 5, a single shape only, however, being required for either rights or lefts, so that the total number of shapes required of refractory bricks is very small.

As above mentioned a horizontal joint 19 is provided between vertically adjacent panels and a similar space or joint 18 likewise is provided between horizontally adjacent panels. This provides for the expansion and contraction both vertically and horizontally of any individual panel independently of its neighbors. Preferably a yielding packing 26 is placed in each vertical joint immediately in front of a hanger 8, and a similar packing is also used in the joints 19 and in front of the T-bars 15, 16 and 17. Such a packing may, for example, be made of a mixture of approximately equal parts of asbestos fibre and fire clay. It serves both to close up the expansion joints and make an approximately tight wall and also to protect the structural metal members from the heat and gases generated in the combustion chamber. At the same time the packing yields sufficiently to permit the expansion of the panels. Such packing may also be used immediately 100 behind the key blocks 24.

A wall of this construction can be set up or built rapidly and it has the important advantage of requiring relatively little metal in proportion to the area of the wall surface. The provision made for the expansion and contraction of the metal parts which support the front section or lining of the wall and of the panels or units of this wall also are important practical advantages. In addition, 110

the panel construction and the mounting of the blocks in the panels facilitates the making of repairs and avoids any necessity of disturbing any part of the rear wall section for this purpose.

It should also be noted that the hangers and structural steel members are so arranged that they offer relatively little obstruction to the free flow of air through the air space between the front and rear sections of the wall. The construction also provides for the convenient installation of horizontal baffles if desired. For this purpose brackets 28 may be used, as best shown in Figs. 1, 3 and 5, each bracket having a portion to fit on the upright flange of the channel 3 and including a forward edge or lip to rest on the reduced rearward edge of one of the bars 9. Plates 30, Fig. 5, may be placed on these brackets, the latter having lugs 31 to assist in holding the plates in position, and baffle bricks, one of which is shown at 32 in Fig. 3, may then be supported in a horizontal course on the plates. Such baffling may be used at any of the horizontal beams 3.

Vertical baffling may also be provided in the same way by mounting brackets 28 one above the other on successive beams 3 and arranging the baffle bricks in vertical series. Practically any arrangement of baffling desired, therefore, may be conveniently installed.

It may be desirable to use brackets 33 under the horizontal beams 3 to give them added strength and to reduce the weight of these members that otherwise would be required to carry the front wall section.

While I have herein shown and described a preferred embodiment of my invention, it will be understood that the invention may be embodied in other forms without departing from the spirit or scope thereof.

Having thus described my invention, what I desire to claim as new is:

1. A furnace wall comprising, in combination, a structural steel frame at the back of the wall, said frame including horizontal beams, a plurality of supports mounted on said beams in a substantially upright plane, a plurality of horizontal bars mounted on and connecting each pair of adjacent supports, and a wall facing including refractory bricks located at the fire side of the wall and held in alinement with each other by their engagement with said bars.

2. A furnace wall comprising front and rear wall sections, a structural steel frame in said rear section, a plurality of downwardly extending supports mounted on said frame in substantially horizontal alinement with each other, a plurality of horizontal bars connecting the members of each pair of adjacent supports and mounted on them, and refractory blocks in the front section of said

wall engaging said bars and held by the bars in alinement in said wall at the fire side thereof.

3. A furnace wall comprising front and rear wall sections, a structural steel frame in said rear section, a plurality of downwardly extending supports mounted on said frame in substantially horizontal alinement with each other, a bottom bar connecting each pair of adjacent supports and mounted on them near their lower ends, additional bars connecting each pair of adjacent supports and located parallel to said bottom bar and spaced from it and from each other, a course of refractory bricks resting on said bottom bar, and additional courses of refractory bricks above said first mentioned course and held in alinement in said wall by said additional bars.

4. A furnace wall comprising front and rear wall sections with an air space between them, a structural steel frame in said rear section, said frame including horizontal beams, a plurality of supports mounted on said beams, each of said supports including a main portion located in said front wall section and another portion extending across said air space and connecting said main portion with one of said beams, horizontal bars connecting adjacent supports and mounted on them, and refractory bricks located in said front wall section at the fire side of the wall and held in place by said bars.

5. A furnace wall comprising front and rear wall sections with an air space between them, a structural steel frame in said rear section, said frame including horizontal beams, a plurality of hangers suspended on said beams, a plurality of horizontal bars connecting the members of each pair of adjacent hangers and supported on said hangers in definite vertical positions in the wall, and refractory blocks in the front section of said wall engaging said bars and held by them in alinement in said wall.

6. A furnace wall comprising front and rear wall sections with an air space between them, a structural steel frame in said rear section, said frame including horizontal beams, a plurality of hangers suspended on said beams, a plurality of horizontal bars connecting the members of each adjacent pair of hangers and supported by them, the hangers having sockets in which the ends of said bars are removably positioned, and refractory blocks located in and forming part of the front section of said wall and held in alinement by their engagement with said bars.

7. A furnace wall having a front wall section comprising a plurality of panels located closely adjacent to each other and each including a plurality of horizontal courses of refractory bricks, a plurality of horizontal bars holding said courses of each panel in alinement in said front section, supports spaced apart horizontally on which the opposite ends

of said bars for the respective panels are mounted, a rear wall section, and a structural steel frame behind said front section on which said supports are mounted.

- 5 8. A furnace wall having a front wall section comprising a plurality of panels located closely adjacent to each other and each including a plurality of horizontal courses of refractory bricks, a plurality of horizontal bars holding said courses of each panel in alinement in said front section, supports spaced apart horizontally on which the opposite ends of said bars for the respective panels are mounted, a rear wall section spaced from 70 said front wall section, and a structural steel frame behind said front section on which said supports are mounted.

9. A furnace wall comprising front and rear wall sections with a space separating 20 them, said front section including a plurality of panels located closely adjacent to each other and each including a plurality of horizontal courses of refractory bricks, a plurality of horizontal bars holding said courses of 25 each panel in alinement in said front section, hangers on which the opposite ends of said bars for the respective panels are mounted, said hangers having sockets in which the ends of the bars are loosely positioned, and a structural steel frame in said rear wall section on 30 which said hangers are mounted.

10. A furnace wall comprising front and rear wall sections with a space separating them, said front section including a plurality 35 of panels located closely adjacent to each other and each including a horizontal course of refractory bricks, horizontal bars for holding said courses of bricks in alinement in the wall, hangers spaced apart horizontally and 40 on which said bars are mounted, and a structural steel frame in said rear wall section on which said hangers are suspended.

11. A furnace wall comprising front and rear wall sections with a space separating 45 them, said front section including a plurality of panels located closely adjacent to each other and each including a horizontal course of refractory bricks, horizontal bars for holding said courses of bricks in alinement in the 50 wall, supports spaced apart horizontally and on which said bars are mounted for expansion and contraction relatively to said supports, said panels being separated from each other by expansion joints, and a structural steel 55 frame in said rear wall section on which said supports are mounted for expansion and contraction relatively to the frame.

12. A furnace wall comprising front and rear wall sections with a space separating 60 them, said front section including a plurality of panels located closely adjacent to each other and each including a horizontal course of refractory bricks, horizontal bars for holding said courses of bricks in alinement in the 65 wall, hangers spaced apart horizontally and

on which said bars are mounted for expansion and contraction relatively to said supports, the bricks in said courses being disengageable from their respective bars by movement approximately parallel to the plane of the wall, courses of key bricks cooperating, respectively, with the previously mentioned courses of bricks to lock the latter against disengagement from their respective bars, said key bricks being readily removable from the wall at the fire side thereof to permit the removal of the other bricks, and a structural steel frame in said rear wall section on which said hangers are mounted. 75

13. A furnace wall comprising front and rear wall sections with an air space separating them; a structural steel frame in said rear section; hangers suspended on said frame and including upper end portions extending across said air space, main portions located 80 in the front wall section and lower end portions extending across said air space and resting against said frame; a plurality of horizontal bars connecting the members of each pair of adjacent hangers, and refractory blocks in the front section of said wall engaging said bars and held by them in alinement 85 in the wall at the fire side thereof. 90

14. A furnace wall comprising front and rear wall sections with an air space separating them; a structural steel frame in said rear section; hangers suspended on said frame; a plurality of horizontal bars connecting the members of each pair of adjacent hangers, refractory blocks in the front 100 section of said wall engaging said bars and held by them in alinement in the wall at the fire side thereof, and brackets supported on said frame and associated with certain of said bars for supporting baffle bricks in the air space between said front and rear sections. 105

15. A furnace wall comprising front and rear wall sections, a structural steel frame in said rear section, a plurality of downwardly extending supports mounted on said frame in substantially horizontal alinement with each other, a bottom bar connecting the members of each pair of adjacent supports and mounted on them, a horizontal course of refractory bricks supported on said bottom bar and forming part of said front wall section, additional courses of refractory bricks mounted above said first mentioned course and supported by said bar, and means for holding said additional courses in alinement in the 115 wall. 120

16. A furnace wall of the structural steel type having a front wall section comprising a plurality of panels located closely adjacent to each other, each of said panels including a plurality of horizontal courses of refractory bricks, horizontal supports for said respective panels, each support carrying the bricks of an individual panel, structural steel supports spaced apart horizontally and carrying said 125 130

horizontal supports, and a structural steel frame on which said supports are mounted.

17. A furnace wall of the structural steel type having a front wall section comprising
5 a plurality of panels located closely adjacent to each other, each of said panels including a plurality of horizontal courses of refractory bricks, horizontal supports for said respective panels, each support carrying the
10 bricks of an individual panel, hangers carrying said horizontal supports, and a structural steel frame on which said hangers are suspended.

18. A furnace wall comprising front and
15 rear wall sections, said front section including a plurality of panels located closely adjacent to each other and each including horizontal courses of refractory bricks, said panels being separated from each other by ex-
20 pansion joints, structural steel supports for said front wall section including structural members located at said joints, and refractory insulating material protecting said members at said joints from the heat of the furnace.

25 19. A furnace wall comprising front and rear wall sections, said front section including a plurality of panels located closely adjacent to each other and each including horizontal courses of refractory bricks, said
30 panels being separated from each other both vertically and horizontally by expansion joints permitting expansion and contraction of the panels both vertically and horizontally with reference to each other, structural steel
35 supports for said front wall section including structural members located at those joints which permit horizontal expansion of the panels, and refractory packings located in front of said supports and at the inner edges
40 of said joints for protecting said members from the heat of the furnace.

OSCAR NYGAARD.
